ASSIGNORS TO HUB METAL BED CO., OF CHICAGO, ILLINOIS, A CORPORATION OF
ILLINOIS

FOLDING BED

Application filed January 15, 1931. Serial No. 508,872.

Our invention relates to new and useful improvements in folding beds and more particularly to the type of folding bed known as the roller type of disappearing bed.

More specifically our invention is directed to improvements on the type of folding bed that is mounted on a base having a plurality of rollers thus enabling it to be moved from the closet in which it is hidden when in folded or upright position to any desired location in the room where it may be unfolded to horizontal position for use.

Heretofore folding beds of this type have required heavy counterweights mounted on the base to prevent the bed from upsetting when unfolded due to the moving of the center of gravity to a position without the base. There have been some attempts by inventors to overcome this difficulty by supplying additional or supplemental extension legs which move outward into extended position when the bed is lowered but such attempts have not met with much success.

Our invention is directed to means for causing the base of a bed of this type to extend in size as the bed is lowered so that the center of gravity remains within the base and the stability of the whole structure is maintained. Also we provide spring means for controlling the action of folding and unfolding the bed so that a balance between the two operations is effected.

An object of our invention is to provide an extensible telescopic base for folding beds.

Another object is to provide a bed frame mounted pivotally on such a telescopic base with connecting members between the frame and base whereby the base is extended as the bed frame is swung to horizontal position and telescoped as the frame is swung to vertical position.

Another object is to provide in a bed of this type spring members which resist the movement of the frame to horizontal position

and the base to extended position and tend to return them to folded position.

Another object is to provide a folding bed of this type of light weight and counter-balanced to facilitate operation.

Other objects and advantages will be apparent from the following more detailed description.

Referring to the drawings:

Fig. 1 is a side elevation of a bed constructed in accordance with our invention in folded or upright position.

Fig. 2 is a side elevation showing the bed in unfolded horizontal position.

Fig. 3 is a horizontal section on line 3—3 of Fig. 2, the telescoped position of the base members being shown in dotted lines.

Fig. 4 is a cross section on a larger scale along line 4—4 of Fig. 3.

Fig. 5 is a section along line 5—5 of Fig. 4.

Fig. 6 is a section along line 6—6 of Fig. 4.

Fig. 7 is a horizontal section on line 7—7 of Fig. 2.

Referring now more particularly to the drawings, 1 is the base, 2 is the head end, 3 is the rectangular bed spring frame having cross bar 3a and 4 is one of a pair of legs pivotally attached to the foot end of the frame 3. To the base 1 at each corner there are pivotally secured swivel rollers 5.

The base 1 comprises a rectangular member having parallel sides 6, 7, 8 and 9 and a U-shaped member having two parallel side arms 10 and 11 and a connecting bar 11a.

The sides 6 and 7 are constructed of hollow rectangular metal forming sleeves or slide-ways adapted to slidably receive the arms 10 and 11 of the U-shaped member.

The spring frame 3 is pivotally mounted at each side to vertical supporting standards 12 at points 13.

The supporting standards 12 extend inwardly and upwardly from the sides 6 and 7 respectively and are reenforced by brackets 14 which are secured to side 8, (see Fig. 3). Mounted on the ends of arms 10 and 11 are

rollers 15 adapted to fit within the hollow sides 6 and 7. Mounted on the upper surface at the inner ends 16 and 17 of the sides 6 and 7 respectively are rollers 18 the lower portions of which extends down into the hollow sides 6 and 7 and are adapted to bear against the upper surfaces of the arms 10 and 11 respectively. In the cross bar 3a of the spring frame 3 are a plurality of holes 19 in any of which may be fastened one end of the spiral expansion springs 20, the other ends being fastened respectively to the members 14 at approximately their centers. Smaller spiral expansion springs 21 are positioned and secured between depending eyes 22 and 23 attached to members 6 and 10 and 7 and 11 respectively. Pivoted at a point 31, on the frame 3 above 13 when the bed is in folded position, is one end of a connecting rod 24 pivotally secured at its other end to a bracket 25 on the U-shaped frame adjacent the point of juncture of members 10 and 11a. A similar connecting arm is on the other side of the bed. Pivoted connected to a bracket 26 fastened in the middle of member 8 is a metal rod 27. Similarly connected to a bracket 28 located on the central portion of a cross bar connecting the folding legs 4 is a sleeve 29 adapted to receive slidably within it the rod 27. Adjustably secured to rod 27 is a stop member 30.

Having described in detail the elements of our invention, we will now describe its operation.

When not in use the bed is kept in any desirable recess, closet or the like in the folded position shown in Fig. 1. To use the bed it is only necessary to move it on its rollers to the desired location, grasp the frame 3 near the foot of the bed and swing it downwardly to horizontal position. It is apparent that as the frame 3 is moved from vertical to horizontal position on its pivots 13 the connecting rods 24 cause the U-shaped base member comprised of members 10, 11, and 11a to slide outwardly from within the slideways of the sides 6 and 7, thus effectively increasing the area of the base so that the center of gravity remains within it and the structure remains stable. The rollers 15 and 18 minimize vertical friction between members 10 and 6 and 11 and 7 and the rollers 5 allow movement on the floor thus insuring ease of operation. As the bed is lowered to usable position the springs 20 and 21 expand thus counteracting the force of gravity upon the descending bed frame and producing a force which tends to return the frame to vertical position and the arms of the U-shaped member within the slideways. Thus a state of counterbalance is approached and results in only a slight force being required to either lower or raise the bed. It is also apparent that the distance between brackets 26 and 28 decreases as the bed is lowered and increases

as it is raised. Thus as the stop member 30 is secured in position on rod 27, it contacts with the sleeve 29 as the bed is lowered and forces the legs 4 into supporting position for the bed frame and locks them in this position. When the operation is reversed gravity causes the legs to swing back to closed position.

The tension of expansion spring 20 may be varied by hooking the head end of spring 20 into the various holes 19 provided in the cross bar 3a. In this way counterbalance may be maintained even though the weight of spring frame 3 may change.

We claim:

1. In a folding bed an extensible base mounted on wheels, comprising hollow rectangular slide-ways, connected arms slidably mounted in said slide-ways, a roller mounted on the inner end of each of said arms having rolling contact with an interior surface of said slide-ways, and enclosed rollers mounted on and extending partially within each of said slide-ways and adapted to bear against said arms, a spring frame pivotally mounted on said slide-ways, a single connecting rod therefor on each side pivotally secured to the arm on that side and to said frame and thereby adapted to cause the base to lengthen as the frame is pivoted to horizontal position and a spring connecting each slide-way and the arm mounted therein adapted to cause the base to shorten as the frame is pivoted to vertical position.

2. A folding bed comprising a base mounted on swivel wheels, vertical supporting members extending upwardly from said base, a spring frame pivotally mounted on said members, hollow rectangular slide-ways in said base, connected arms slidably mounted in said slide-ways and forming part of said base, a roller mounted on the inner end of each of said arms having rolling contact with an interior surface of said slide-ways, an enclosed roller mounted on and partially within each of said slide-ways adapted to bear against said arms, connecting rods, one end of each pivotally connected to an arm, the other end similarly connected to the spring frame and adapted to cause said arms to slide away from slide-ways as the spring frame is pivoted to horizontal position, springs adjustably mounted on and connecting the head of said spring frame and said vertical supporting members and springs connecting said slide-ways and said arms adapted to cause said arms to slide into said slide-ways as the spring frame is pivoted to vertical position.

3. In a folding bed an extensible base mounted on rollers comprising hollow slide-ways, connected arms slidably mounted in said slide-ways, rollers mounted on and extending within each of said slide-ways and having rolling contact with said arms, a

spring frame pivotally mounted on said slideways, connecting rods one end of each pivotally fastened to said arms and the other ends pivotally fastened to said spring frame
5 adapted to cause said base to extend as said spring frame is pivoted to horizontal position, springs connecting each of said arms with its respective slideway adapted to cause them to retract as the spring frame is pivoted
10 to vertical position and connecting springs mounted on the head of said spring frame and the slideways adapted to resist the pivoting of said spring frame to horizontal position.
